(57) **CLAIM**

We claim the ornamental design for a capacitor microphone, as shown and described.

DESCRIPTION

FIG. 1 is a top perspective view of a capacitor microphone of the present invention;

FIG. 2 is a first side view thereof, wherein the second side view is a mirror image thereof;

FIG. 3 is a front view thereof, wherein the rear view is a mirror image thereof;

FIG. 4 is a top view thereof; and,

FIG. 5 is a bottom view thereof.
